DESIGN FOR A COMBINED MULTIPLE DISPLAY RECEPTACLE AND INDIVIDUAL ARTICLE CONTAINER

Hyman Schiller, New York, N. Y.

Application February 1, 1936, Serial No. 60,945

Term of patent 3½ years

To all whom it may concern:

Be it known that I, Hyman Schiller, a citizen of the United States, residing at New York city, in the county of New York and State of New York, have invented a new, original, and ornamental Design for a Combined Multiple Display Receptacle and Individual Article Containers, of which the following is a specification, reference being had to the accompanying drawing forming part thereof.

Fig. 1 is a perspective view of a combined multiple display receptacle and individual article containers in partially open position, showing my new design.

Fig. 2 is a top plan view of the same in fully open position.

Fig. 3 is a perspective view of the same, in closed position.

I claim:

The ornamental design for a combined multiple display receptacle and individual article containers, as shown.

In testimony whereof I have affixed my signature.

HYMAN SCHILLER.
